UNITED STATES PATENT OFFICE

2,026,655

CAR HEATER

Herbert C. Rice, Detroit, Mich., assignor to General Motors Corporation, Detroit, Mich., a corporation of Delaware

Application March 11, 1935, Serial No. 10,376

6 Claims. (Cl. 257—137)

This invention relates to heating apparatus and more particularly to heating apparatus that is used to heat motor cars.

The use of heaters of different types in motor cars is, of course, common, but it is difficult to attain a satisfactory circulation of the heated air to different parts of the car.

It is an object of my invention to provide a heating unit which has a plurality of air inlets and outlets at different localities to give a better air circulation.

It is a further object to provide a plurality of radiator elements in my heater and a plurality of air circulating blower elements.

It is a still further object to provide a large air flow to carry the heat to the car.

With these and other objects in view, which will become evident as the description proceeds, my invention is embodied in the following construction as described in the specification and claims and illustrated in the accompanying drawings, in which:

Figure 1 is a side elevation of the forward portion of a car with my heater attached, parts being shown in section.

Figure 2 is an enlarged front elevation of the heater taken on the line 2—2 of Figure 1.

Figure 3 is a longitudinal section of the heater taken on line 3—3 of Figure 2.

Figure 4 is a sectional view taken on the line 4—4 of Figure 3.

Figure 5 is a sectional view taken on the line 5—5 of Figure 3.

Figure 6 is a sectional view taken on the lines 6—6 of Figures 3 and 5.

Figure 7 is a sectional view taken on the line 7—7 of Figure 3.

A motor car frame 2 supports at its forward end a motor 4 and a radiator 6, the latter being connected to the motor by the usual rubber connecting hoses 8 and 10. To the rear of the motor is the dash board 12 upon which is secured a heater 14 which is the subject of my invention. The heater is secured to the dash board by bolts 16 and the inlet pipe 18 is connected to the water in the motor head through a pet cock 20 and a tube 22. The outlet pipe 24 is connected to the lower radiator header 26 by a tube 28.

The heater has a substantially cylindrical outer casing 30 which is peripherally secured at one end to a supporting bracket 32 which in turn supports the whole on the dash by bolts 16. It is thus evident that the body of the heater extends at right angles from the dash. The end of the casing is open, thus allowing air to flow from the

outside around the arms of the bracket and into the center.

The opposite end of the casing has a ring 66 fitting inside and secured by pressing through openings in the ring, offset portions 36 of the casing. A front panel 38 is secured to the forward face of the ring by suitable screws 40. This front panel has a decorative edge portion and a pair of doors 42 pivoted in the edge as at 44 to control the flow of air from the front of the 10 heater.

The inside of the casing is formed into two separate compartments by a partition 46 substantially midway between the ends. This partition has a circular opening in the center thereof in 15 which is supported a motor 48. Angled brackets 50 secured to the partition by bolts 52 have portions 54 that extend along the motor casing to prevent it from tipping. The motor casing extends on both sides of the partition and an armature shaft 56 extends also out beyond the casing in both compartments and supports two fans 58 and 60, one on each end.

In each compartment also there is a conventional radiating element 62 and 64 respectively. 25 In the forward or left compartment in Figure 3 the radiator is supported at the front of the compartment by the irregular shaped bracket 66 around the radiator which extends to the inside of the casing and is secured thereto. A similar 20 bracket 68 is used to support the radiator 64 at the approximate center of the rear compartment.

Extending from the rear face of the radiator in the forward compartment is a circular housing 70 which surrounds the fan 58 and acts to direct 35 the air through the radiator. In the casing 30 to the rear of the fan 58 and above the motor are a series of openings 72 at which air may enter from the outside. It is therefore evident that in the forward compartment the air enters the openings 40 72 and is pulled in by the fan 58, goes through the circular housing 70, through the porous radiator 62 and out the front of the whole.

Extending forward from the rear radiator element 64 is a circular fan housing 74 which surrounds the fan 60 in the same manner that the housing 70 surrounds the fan 58. In this case the lower portion of the case 30 below the motor and ahead of the fan 60 has a series of louvres 76 45 therein for the expulsion of air, the air in this 50 case being drawn through the open back of the casing, through the radiator and fan and is discharged from the bottom of the casing. As can be readily seen in Figures 4 and 5, the louvres 76 extend up on one side of the casing to discharge 55

some air to one side, the particular side being governed by the location of the heater in the car, which is usually on the right. The flow of air through both compartments is shown by the arrows.

5 The inlet pipe 18 and the outlet pipe 24 are connected to both the radiating elements to supply hot water thereto from the cooling system of the motor in a conventional manner.

10 It will thus be seen that I have provided a multiple unit heater in which there are two separate radiator elements, two fans to cause air flow through the radiators and independent inlets and outlets for the air in different directions. The 15 air is pulled through one radiator and blown through the other, cool inlet air passing over the forward portion of the motor to prevent its becoming overheated. The control of the motor may be, by any conventional means, through 20 cables 78. By thus splitting up the air stream, I obtain a higher heat transfer to the air from the heater per unit of air and considerably less air friction through the radiators to give increased heat as well as better distribution from 25 the heater, and obviously with two sets of fan blades the flow of air from the heater is high.

It will be further seen that I have provided a heater which discharges the air both outwardly and downwardly to give a combination of out-draft and down-draft from the heater. If only 30 one heating element were used, the opening in the bottom of the heater would be positioned adjacent the front opening of the heater to give this result.

35 I claim:

1. In a heater, a casing, a plurality of air heating and circulating units therein, separate air inlets and outlets for each unit facing in different directions from the casing, the inlets being 40 at right angles to each other and their respective outlets, so that air is taken in in different directions and discharged in still further different directions.

2. In a heater, a casing, a plurality of radiator

elements therein, a plurality of air propelling means between the radiating elements for causing air to circulate through the radiators, a common motor for actuating the air propelling means and a plurality of independent air inlets 5 and outlets on corresponding sides of the radiating elements whereby air is drawn through one of the radiator elements and forced through the other.

3. In a heater, a substantially cylindrical cas- 10 ing, a plurality of radiating elements, a plurality of air circulating fans and a common motor therefor, all aligned on the axis of the casing, air inlets in the top and rear of the casing and air outlets at the front, bottom and one side to 15 give a good distribution of air discharged from the radiators by the fans.

4. A heater comprising a casing, a partition at the approximate center of the casing, a motor supported by the partition, a fan on each end of 20 the motor shaft, a radiating element adjacent each fan, a fan housing carried by each radiator element to direct the flow of air, openings at the rear and bottom of the casing acting as air inlet and outlet respectively of the rear radiator and, in the top and front for the forward radiator element and adjustable means on the front of the casing for varying the flow of air therefrom.

5. A heater comprising a casing, means within 30 the casing for circulating air therethrough, means within the casing for heating the air in two separate streams, and means for discharging the air from the casing one outwardly and one downwardly at right angles to each other. 35

6. A heater comprising a casing, means within the casing for circulating air therethrough, means within the casing for heating the air, and a plurality of inlet and outlet openings for air flow whereby the air is taken in at different 40 points and is discharged in two separate streams one outwardly and one downwardly therefrom at right angles to each other.

HERBERT C. RICE.

CERTIFICATE OF CORRECTION.

Patent No. 2,026,655.

January 7, 1936.

HERBERT C. RICE.

It is hereby certified that error appears in the printed specification of the above numbered patent requiring correction as follows: Page 2, second column, line 32-33, claim 5, strike out the words "in two separate streams" and insert the same after "air" in line 33, same claim; and that the said Letters Patent should be read with this correction therein that the same may conform to the record of the case in the Patent Office.

Signed and sealed this 11th day of February, A. D. 1936.
